UNITED STATES PATENT OFFICE.

ALFRED CARLSON, OF KLAMATH FALLS, OREGON.

GEARING.

1,203,481.

Specification of Letters Patent. Patented Oct. 31, 1916.

Original application filed April 10, 1915, Serial No. 20,473. Divided and this application filed October 27, 1915. Serial No. 58,212.

To all whom it may concern:

Be it known that I, ALFRED CARLSON, a citizen of the United States, residing at Klamath Falls, in the county of Klamath, and State of Oregon, have invented certain new and useful Improvements in Gearing, of which the following is a specification.

This invention relates to improvements in driving mechanisms adapted for converting rotary into reciprocatory motion of the type disclosed in my co-pending application Serial Number 20,473, filed April 10, 1915, of which this case is a division.

Among other objects in view the device is designed to provide a compact system of gearing capable of being inclosed within a housing or casing so as to operate in a lubricant bath, provision being made for effectively preventing the escape or loss of the lubricant by so arranging the parts as to preclude injury owing to this cause. It is comprehended, furthermore, to so construct the mechanism as to obtain a maximum throw of the reciprocated member, which is a desideratum in constructions of this type.

These and such other objects as may hereinafter appear are attained by the novel construction, combination and arrangement of parts to be hereinafter specifically described and claimed.

Reference will now be had to the accompanying drawings forming a part of this specification, wherein:

Figure 1 is a vertical sectional view through an embodiment of this invention; Fig. 2 is a similar section taken about on the plane indicated by the line 2—2 of Fig. 1; Fig. 3 is a vertical sectional view through a modified form of the apparatus; Fig. 4 is a vertical section on the line 4—4 of Fig. 3; Fig. 5 is a view in elevation, partly broken away and shown in section, showing an embodiment of the invention differing from the construction disclosed in Fig. 1 only in respect to its connection with the reciprocatory member; Fig. 6 is a vertical section on the line 6—6 of Fig. 5; Figs. 7 and 8 are horizontal sectional views taken on the lines 7—7, and 8—8 of Figs. 5 and 6, respectively; and Fig. 9 is a detail perspective view of the detachable connection intermediate the reciprocatory member and its actuating gear element.

Throughout the following detail description and on the several figures of the draw-

ings, similar parts are referred to by like reference characters.

Specifically describing my invention and referring particularly to Figs. 1 and 2, the numeral 1 designates a casing of a suitable form and size to house the transmission gearing of my device, the casing being provided at one side with a cover 2 bolted or otherwise secured in position thereon. At its other side the casing is formed with a lateral extension 3 on which is rotatably mounted the driving member for the said gearing more particularly described hereinafter. This driving member, in describing this particular embodiment of my invention, consists of the driving element such as the wheel hub 5 of a windmill (not shown), composed of an inner and outer section bolted together by the fastening members 6 centrally thereof. A suitable bearing collar 7 is interposed between the interior wall of the hub and the extension 3 for facilitating rotation of the wind wheel, said wheel being connected through its hub to the end of a drive shaft 8 revolvably mounted within a longitudinal bore of the extension 3. The inner side of the hub 5 is formed with a brake flange or drum 9 through which the rotation of the driving element may be controlled where the mechanism is adapted for windmills.

The inner end of the shaft 8 extends into the hollow portion of the casing 1, which it may be here stated is adapted to contain a lubricant, and keyed or otherwise secured to the shaft is the driving pinion 10 meshing with a spur gear 11 loosely carried by the supporting shaft 12, in turn secured to the supporting member or arm 13 loosely mounted upon the drive shaft 8 intermediate the pinion 10 and the rear wall of the casing 1, said arm having a hub 13' journaled in said casing. The opposite end of the shaft 12 has loosely mounted thereupon a large spur gear 14 which is made fast to the gear 11 in any desired manner, as by means of the fastening members or bolts 15. The gear 14 intermeshes with the internal gear teeth 16 formed annularly about the inner wall of the casing 1.

It will be obvious from the foregoing description that the gears 11 and 14 have planetary movement about the driving pinion 10 on the shaft 8, and said gears may be arranged with any desired ratio depending

upon the power required for the work to be accomplished. The gear 14 is provided with a detachable crank pin 17 to which is connected the pitman 18 coöperating with a vertical groove 19 formed in the cover 2. By this construction and arrangement of parts the pitman just mentioned is operated in a direct vertical path which is one of the particular features of my invention. I also 5
10 lay stress upon the fact that the casing 1 is of a character to hold a sufficient supply of lubricant whereby the gears operate substantially noiselessly and with a minimum amount of wear. The casing 1 is formed 15 with a duct 20 for feeding the lubricant to the shaft 8. The pitman 18 is surrounded with a packing 21 held in place by the gland 22 screwed into the base of the casing 1 which is mounted upon the turn table 23 20 of a wind mill or other support according to adaptation of the driving mechanism hereinbefore set forth.

Owing to the fact that in this type of construction of the mechanism as above described 25 it is requisite that the packing 21 be held in place and the wear thereon taken up from time to time, it is sometimes a disadvantage since unless these precautions are taken the lubricant is likely to escape from 30 the casing and cause unnecessary wear and injury to the gear elements. To eliminate the wear and adjustment, therefore, I have devised a slightly different arrangement which is shown most clearly in Figs. 5 and 6 35 of the drawings. In this construction the gear members and elements maintain their relative position and perform their identical functions as the equivalent elements in the form first described. However, instead 40 of connecting the gear member 14 directly to the reciprocating member, which may be any pitman connection or which is the pump rod in the construction of a wind mill, the detachable crank pin 17 is connected to the 45 lower end of a rod 24 which extends upwardly and into the superposed casing extension 1^a detachably connected to the casing 1 as indicated at 25. The upper end of the rod 24 is connected by means of the 50 pins 26 to the upper end of the reciprocating member 18. This rod extends downwardly through the support for the casing and is held in place by means of the cover 2^a provided for the casing 1. This cover constitutes 55 guide means both for the rod 24 and the reciprocating member 18, as will be observed most clearly by reference to Fig. 8 of the drawings. The cover 2^a is preferably hingedly connected to the casing at 27 and 60 there is provided a removable cap 2^b which is attached to the outer face of the cover and extends over the casing extension 1^a. It may be stated at this point that to disconnect the reciprocating member for the 65 purpose of opening the cover 2^a for access

to the internal gears, it is contemplated that the upper portion of the reciprocating member will be provided with a detachable section which upon being disconnected below the turn table 23 and relieved of the pins 26, after displacement of the cap 2^b, said section of the reciprocating member may be withdrawn downwardly from position. The cover may then be swung upon its hinge after removal of its fastening bolts 7 and this relieves the connecting rod 24 and enables access to the interior of the casing. In this form it will be obvious that no packing is required for the pump rod or reciprocating member 18, and escape of the oil 8 from the casing 1 is quite adequately prevented.

In Figs. 3 and 4 is disclosed a modified form of this invention designed with a view to obtaining a maximum thrust for the reciprocating member. The parts of this construction are also identical with those of the type shown in Fig. 1, excepting that instead of connecting the detachable crank pin 17 directly to the reciprocating member, said crank pin is provided with a rack pinion 28, said pinion meshing at one side with a rack 29 formed upon the cover 30 provided for the casing of this device. This rack constitutes a stationary element and during rotation of the planetary gear member 14 around its internal gear path the pinion 28 is caused to travel upwardly of the rack 29. The reciprocating member 18 for this type of construction is provided at its upper end with a rack section 18^{''} intermeshing with the rack pinion 28 aforesaid at the opposite side of the rack 29. The rack section 18^{''} coacts with a guide projection 31 on the cover so that it is maintained in vertical line during reciprocating movement under the actuation of the rack pinion 28. This section 18^{''} being movable has imparted to it a thrust movement which is double the length of the rack 29, or more strictly speaking the extent of movement of the pinion 28 on said rack.

The operation of this device will be apparent from the foregoing description and its adaptation to any mechanism for converting rotary into reciprocating motion will also be obvious to those skilled in the art to which the invention refers.

Having thus described the invention, what is claimed is:—

1. In actuating mechanism of the class described, the combination of a driving member, a support therefor comprising a casing on which said driving member is journaled, a driving shaft connected at one end to the driving member and extending into the casing, a drive pinion secured to the shaft, a reciprocating member operable in said casing, a supporting member journaled on the driving shaft, a gear element

- loosely carried by said supporting member, and operatively connected to the reciprocatory member, and a casing rack with which said last mentioned gear member 5 operates to impart reciprocation to the reciprocatory member on rotation of the driving shaft.
2. In mechanism of the class described, the combination of a driving wheel, a hollow casing formed with a lateral bearing extension on which the drive wheel is mounted, a shaft revolvably mounted in said extension and connected to the wheel at one end, a drive pinion carried by the inner end of said 15 shaft, a gear member meshing with the drive pinion, gear teeth in said casing with which said last mentioned gear member is operatively connected, a support for said gear member carried by the shaft intermediate 20 the drive pinion and the casing, and a driving connection connected to the gear member.
3. In mechanism of the class described, the combination of a driving wheel, a casing 25 associated therewith on which said wheel is rotatably mounted, a drive shaft journaled in said casing and connected with the wheel, a drive pinion on said shaft disposed in the casing, a spur gear intermeshing with said 30 drive pinion, a support for said spur gear journaled on the shaft, a relatively larger spur gear fast to and concentric with the first mentioned spur gear, gear teeth formed within said casing with which the relatively 35 large spur gear intermeshes and forming a path of travel therefor, a pitman connected to the spur gears, and guide means for said pitman, said guide means constituting a cover for the casing.
4. In mechanism of the class described, the combination of a rotatable driving member, a support therefor, power transmission elements mounted on said support including a drive shaft to which the driving member 45 is connected, a reciprocatory member, and an actuating pinion operably connected to the reciprocatory member for travel longitudinally thereof, a member rotatable about the axis of the drive shaft and supporting
- said pinion, and means on the support with 50 which the pinion co-operates for imparting reciprocation to said reciprocatory member.
5. In mechanism of the class described, the combination of a rotatable driving member, a support therefor comprising a casing, 55 power transmission elements in said casing including a drive shaft connected to said driving member, a toothed reciprocatory member, and actuating means interposed between the reciprocatory member and the casing and revolvably carried by the transmission elements for imparting reciprocation to the reciprocatory member comprising a rack and pinion.
6. In mechanism of the class described, 65 the combination of a rotatable driving member, a support therefor comprising a casing, a drive shaft connected to said driving member in the casing, a reciprocatory member, actuating means operably connected to the 70 drive shaft for imparting reciprocation to the reciprocatory member, a stationary element on the casing spaced from and parallel with the reciprocatory member, and a pinion supported by the drive shaft intermediate 75 the reciprocatory and stationary elements, said pinion having driving connection with the reciprocatory member whereby to impart double throw to the latter.
7. In mechanism of the class described, 80 the combination of a rotatable driving member, a support therefor comprising a casing, a drive shaft connected to said driving member, a reciprocatory member terminating in a rack, actuating means operably connected 85 to the drive shaft for imparting reciprocation to the reciprocatory member, a stationary rack on the casing parallel with the reciprocatory member, and a pinion carried by the actuating means aforesaid, said pinion 90 having driving connection with the reciprocatory member whereby to impart double throw to the latter, and guide means in the casing disposed opposite the rack for guiding the reciprocatory member.

95 In testimony whereof I affix my signature.

ALFRED CARLSON.
